UTILITY STAND

Howard D. Brown, Westfield, N. J.

Application September 19, 1951, Serial No. 247,281

5 Claims. (Cl. 248—168)

This invention relates to what I term a utility stand, the purpose of which is to support a can, pail, dish or the like, at a convenient height, so as to render the same accessible to an operator, without the need of bending as is usually the practice in gaining access to such articles when supported upon a floor or surface upon which an operator is standing. More particularly, the invention deals with a device of the character described, which can be arranged upon a supporting surface and, further, which includes a hook end, facilitating the mounting of the device in an angular position with respect to a supporting rail, board, or the like.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a side view of a device made according to my invention, illustrating the same in full lines supported upon a board, rail or similar support, with parts of the construction broken away and in section and indicating in dot and dash lines the mounting of the device upon a supporting surface.

Fig. 2 is a view of the lower end portion of the device, looking in the direction of the arrow 2 of Fig. 1 and omitting the support of Fig. 1.

Fig. 3 is a plan view of the table or platform of the device; and

Fig. 4 is a broken section on the line 4—4 of Fig. 1.

In Fig. 1 of the drawing, I have shown a utility device comprising a pair of leg strips, or bars, 10 and 11, movably coupled at their upper ends by a hinge 12, forming a pivot axis 13, about which a table or platform 14 is adapted to swing and be clamped, as later described.

The strips or bars 10 and 11 are substantially of the same width and the strip 10 is slightly longer than the strip 11, the lower end of the strip 10 having an elongated central aperture 15 for adjustable coupling of a supporting hook 16 therewith. The hook 16 comprises a relatively long arm, or finger, 17, having a curved or recessed central portion 18. A shorter arm 19 of the hook joins the long arm 17 in a crosshead 20 and both arms and the crosshead are reinforced by a continuous rib, as seen at 21. The short and long arms 17 and 19 have parallel portions. The short arm 19 has an upwardly directed flat extension or bracket portion 22, having spaced apertures to receive clamp winged nut bolts 23. The bolts engage U-shaped reinforcing strips 24 on the undersurface of the strip 10, as will clearly appear from a consideration of Figs. 1 and 2 of the drawing.

The leg strip 10 has substantially centrally thereof a rearwardly projecting eye bolt 25 which passes through an aperture 26 in the strip 11. Coupled with the bolt 25 is a long hook brace 27, the free end of which normally engages an eye secured to the strip 11, as seen in full lines in Fig. 1. However, in extending or spreading

2

the legs 10 and 11, the hook 27 is adapted to engage one of a number of eyes 29 on the leg 11 to control the spread of the legs 10 and 11, one with respect to the other in mounting the device on a supporting surface indicated at 30 in dot and dash lines in Fig. 1.

The lower end portion of the leg strip 11 has a cross-plate or strip 31 secured thereto, this strip or plate being substantially of the width of the hook 16, note Fig. 2, and this strip, as well as the lower end of the leg 11 is reinforced by a plate 32, generally of the contour seen in Fig. 2 of the drawing, the plate having a lower flange portion, as at 33.

The strip 31 forms a support for the device engaging the upper surface of a rail, plank or the like 34; whereas, the arm 17 of the hook 16 engages the lower surface thereof, thus supporting the two leg members in the angular position, as illustrated in Fig. 1. The table 14 is clamped in a horizontal position with respect to the upper surface of the support 34 by adjustment around the axis 13 in the manner hereafter described.

The table 14 is generally of the shape illustrated in Fig. 3 of the drawing, one end of the table having contracted walls, upon which is secured a raised retaining flange 35, the flange having an inwardly and downwardly curved hook portion 36, note Fig. 1. This hook portion is adapted to engage the beaded edge of a paint can or the like and, to illustrate diagrammatically the use of the device, I have indicated in dot and dash lines in Fig. 3 at 37 a quart paint can; at 38 a half gallon paint can and, at 39, a full gallon paint can.

Also engaging the lower beaded edges of these cans is a clamp hook 40 adjustable longitudinally of an elongated aperture 41 in the table and opening through one edge thereof as clearly seen in Fig. 3. The upper surface of the table, longitudinally of the aperture 41, has a recess 42 to maintain the lower plate of the clamp 40, below and in alignment with the upper surface of the table, so as to provide a flush mounting of a can on the table.

A winged nut bolt 43 is employed to secure the clamp 40 in different positions. In this connection, it will be understood that sufficient clearances will be provided to facilitate a wide range of adjustment of the table 14 on the pivot 13 and these clearances are not exaggerated in the present showing.

Secured to the lower surface of the table is a yoke-shaped segment 44 which has an aperture registering with the aperture 41, as clearly seen in Fig. 4 of the drawing and the depending side walls of the segment 44 have rounded lower surfaces, as illustrated at 45 in Fig. 1 of the drawing. One hinge butt plate 46 of the hinge 12 has an extended curled end 47 for reception of a winged nut bolt 48 which terminates at and is movable over the round edge 45 of both side plates in adjustment of the table 14. Washers 49 are provided on the bolt 48 so as to facilitate firm clamping of the table 14 on the legs 10 and 11 in different angular positions with respect thereto.

In connection with the adjustment of the table 14, it will be understood that, when the thickness of the support 34 varies, the leg members will assume a different angular position and the table will have to be adjusted to suit this difference in angularity in order to maintain the table in a horizontal position.

The utility device may be mounted in conjunction with vertically disposed supports such, for example, as the side rails of a ladder in supporting a pail or can in accessible position and, in addition to forming supports, the utility device may be utilized as a seat, by simply removing the clamp 40 or, as a support of any type or kind.

Generally in the operation of painting, or in the use of water buckets, pans or the like in performing cleaning

operations, such as washing walls, cleaning windows or the like, a great bit of time is devoted to the bending operation of reaching the pail, can or the like supported upon the surface, upon which the operator is standing. With a utility device of the kind described, this pail, can or the like can be disposed at a height rendering the same accessible without body bending, thus materially facilitating the performance of the painting, washing or other job being performed and also minimizing fatigue in the performance of the operation.

In the illustration in Fig. 1 of the drawing, the support 34 can be the side rail of a scaffolding or planking, such as used by painters and it will be readily apparent that, with a utility device, the paint can can be positioned at a waist-high or similar level to the operator, so that a material distance is saved in the operation of placing the paint brush into and removing the same from a paint can.

Furthermore, in addition to relieving the fatigue of body bending, the painting operation is performed in a much speedier fashion and, still further, a minimum amount of paint will be lost in transmitting the paint from the can to the surface being painted.

From a standpoint of description, the table or platform 14 may be considered a utility member; whereas, the supporting hook 16 can be considered means for mounting the member in connection with a suitable support, adjustment being provided to control engagement of the hook with the support and the position of the utility member with respect to the hook.

Having fully described my invention, what I claim as new and desire to secure by Letters Patent is:

1. A utility stand of the character described, comprising an elongated straight leg member having upper and lower ends, a support engaging U-shaped hook on and extending below said lower end of the leg member for mounting the leg member above and at an inclination to a horizontally elongated support member, said hook having fixedly spaced parallel arms, between which the support member is arranged, the upper end of the leg member having pivot means, a segment mounted on said pivot means, a table on said segment, and means on the leg member adjacent the upper end thereof engaging said segment for adjustably clamping the table on the leg member to maintain said table parallel with respect to the support member on which the hook of said leg member is mounted.

2. A utility stand of the character described, comprising an elongated straight leg member having upper and lower ends, a support engaging U-shaped hook on and extending below said lower end of the leg member for mounting the leg member above and at an inclination to a horizontally elongated support member, said hook having fixedly spaced parallel arms, between which the support member is arranged, the upper end of the leg member having pivot means, a segment mounted on said pivot means, a table on said segment, means on the leg member adjacent the upper end thereof engaging said segment for adjustably clamping the table on the leg member to maintain said table parallel with respect to the support member on which the hook of said leg member is mounted, means on said table for adjustably clamping an article thereon, means adjustably clamping the hook with respect to said leg member, and means reinforcing said last named means.

3. A utility stand of the character described, comprising an elongated straight leg member having upper and lower ends, a support engaging U-shaped hook on and extending below said lower end of the leg member for mounting the leg member above and at an inclination to a horizontally elongated support member, said hook having fixedly spaced parallel arms, between which the support member is arranged, the upper end of the leg member having pivot means, a segment mounted on said pivot means, a table on said segment, means on the

leg member adjacent the upper end thereof engaging said segment for adjustably clamping the table on the leg member to maintain said table parallel with respect to the support member on which the hook of said leg member is mounted, a supplemental leg member mounted on the pivot means of the first leg member, means spaced longitudinally of the supplemental leg member engaged by a part on the first leg member for adjustably coupling the supplemental leg member with the first named leg member, and the supplemental leg member having an aperture to receive the part on the first named leg member.

4. A utility stand of the character described, comprising an elongated straight leg member having upper and lower ends, a support engaging U-shaped hook on and extending below said lower end of the leg member for mounting the leg member angularly with respect to a support, said hook having spaced parallel arms, between which the support is arranged, the upper end of the leg member having pivot means, a segment mounted on said pivot means, a table on said segment, means on the leg member adjacent the upper end thereof engaging said segment for adjustably clamping the table on the leg member to maintain said table parallel with respect to the support on which the hook of said leg member is mounted, a supplemental leg member mounted on the pivot means of the first leg member, means spaced longitudinally of the supplemental leg member engaged by a part on the first leg member for adjustably coupling the supplemental leg member with the first named leg member, the supplemental leg member having an aperture to receive the part on the first named leg member, and a transverse strip on the lower end of the supplemental leg member forming a support for said leg member.

5. A utility stand of the character described, comprising an elongated straight leg member having upper and lower ends, a support engaging U-shaped hook on and extending below said lower end of the leg member for mounting the leg member above and at an inclination to a horizontally elongated support member, said hook having fixedly spaced parallel arms, between which the support member is arranged, the upper end of the leg member having pivot means, a segment mounted on said pivot means, a table on said segment, means on the leg member adjacent the upper end thereof engaging said segment for adjustably clamping the table on the leg member to maintain said table parallel with respect to the support member on which the hook of said leg member is mounted, said table having diverging hook-shaped flange portions, a member adjustable on the table toward and from said flange portions in support of an article on the table, and means adjustably supporting the hook on said leg member.
